PAGE 2

FIG. 3

FIG. 4

FIG. 5

FIG. 6

FIG. 1 is an end elevation of a headphone earpiece, the broken lines are shown for illustrative purposes only;

FIG. 2 is an outside end elevational view thereof;

FIG. 3 is a top plan view;

FIG. 4 is an inside elevational view;

FIG. 5 is a perspective view of the earpiece of FIG. 4; and

FIG. 6 is a perspective view of FIG. 2.

I claim:

The ornamental design for a headphone earpiece, as shown and described.
